UNITED STATES PATENT OFFICE

2,136,412

FLEXIBLE COUPLING

Washington T. Capps, Baltimore, Md., assignor to The Standard Stoker Company, Incorporated, a corporation of Delaware

Original application June 29, 1934, Serial No. 733,142, now Patent No. 2,074,301, dated March 16, 1937. Divided and this application December 22, 1936, Serial No. 117,124

4 Claims. (Cl. 285—11)

This invention relates to flexible couplings which are particularly adapted for use in connection with locomotive stokers. One type of locomotive stoker to which my improved coupling 5 has been adapted is illustrated in my copending application Serial No. 733,142, filed June 29, 1934 which matured into Patent No. 2,074,301 and of which copending application the present application is a true division.

It is an object of this invention to provide a novel manner of connecting a pair of conduits to permit relative movement thereof while securing adequate support for said conduits.

A further object of this invention resides in the provision of a novel flexible coupling comprising a member having an outer spherical surface, a ring carried by said member and having an inner spherical surface fitting over the outer spherical surface of said member, and a sleeve slidable 20 along the outer surface of said ring.

With these and other objects in view, the invention consists of the features of construction, combination and arrangement of parts hereinafter more fully described, reference being had to the 25 accompanying drawings illustrating the invention as embodied in a locomotive stoker, and in which drawings,

Fig. 1 is a plan view, with parts in section, of a locomotive stoker embodying my invention;

Fig. 2 is a side elevation, with parts in section, of the structure illustrated in Fig. 1;

Fig. 3 is a section taken substantially on the line 3—3 of Fig. 1; and

Fig. 4 is a section on the line 4—4 of Fig. 3.

Referring now to these drawings, 1 designates a portion of the locomotive frame, 2 the cab deck, 3 the backhead, 4 the firing opening, and 5 a portion of the rear cab wall of a locomotive, and 6 designates a portion of the tender structure, 6a 40 a portion of the front wall thereof, and 7 the tail or slope sheet of the coal bunker thereof, while A designates the stoker as a whole, which comprises a conveyor or feed unit A' on the tender, an elevator or delivery unit A² on the locomotive, and a transmission or transfer connection or unit A³ between such conveyor and elevator unit.

The conveyor unit A' on the tender comprises a fixed trough-shaped conduit 8 arranged beneath the shovel sheet or floor A⁴ of the fuel bunker or coal bin of the tender and in communication therewith through a longitudinally extending slot or opening A⁵ in said floor. In this conduit or trough 8 is arranged a helical conveyor screw 9 which feeds the fuel forward to the transfer unit 55 A³, from which it is delivered to the elevator unit

A². In practice, the fuel discharge slot or opening A⁵ in the floor A⁴ is provided with adjustable cover plates or slides, which may be opened or closed at any point desired along the length of the opening to regulate the discharge of fuel.

The trough 8 is arranged mainly at one side of the longitudinal center of the deck or floor A⁴ in order that a comparatively wide space or platform portion A⁶ may be provided at the opposite side of the longitudinal center of the floor to afford greater room and convenience for the use of the fireman in shoveling coal for emergency manual stoking operations and to place the parts of the stoker conveyor mechanism in proper operating alignment. The elevator or delivery unit A², which comprises a conduit 10 having a conveyor screw 11 disposed therein, is, on the other hand, arranged in the vertical plane of the longitudinal center of axis of the locomotive, so that the longitudinal axes of the units A' and A² lie in different vertical planes, one displaced laterally to one side of a central vertical plane bisecting the locomotive and tender and the other axially coincident with such vertical plane.

The transfer unit A³, which comprises a conduit section 12 having a conveyor screw 13 disposed therein, extends at an angle to the bisecting vertical plane between the units A' and A² and is provided at its rear end with an offset portion 14 communicating with the side of the conveyor facing the bisecting vertical plane and formed at its rear end with an entranceway and coupling member or connection 15 receiving a tubular projection 16 forming a fuel outlet and coupling member or connection at the forward end of the trough or conduit section 8. The arrangement is thus such that the fuel fed forward from the conduit 8 by the conveyor screw 9 passes into the offset inlet 14 at the rear end of the intermediate conduit 12 from which it is conveyed forwardly by 40 the feed screw 13.

The projection or coupling member 16, as shown particularly in Figs. 3 and 4, has an outer spherical surface arranged to fit within the bushing sleeve or ring 16a disposed between the same 45 and the coupling member 15, the inner surface of said bushing sleeve or ring being of spherical shape and articulately fitting over the complementary shaped spherical surface of the member 16. The outer surface of the bushing sleeve 16a 50 is cylindrical in shape and fits within the cylindrical formation at the rear of the coupling member 15. Thus, the parts 16, 16a form a ball and socket connection between the conduits, and the parts 16a, 15 form a sliding joint therebetween, 55

whereby a combined sliding and articulating joint connection is furnished at this point to adapt the stoker conduits as a whole to have relative backward and forward sliding movements and the conduits 8 and 12 to have relative vertical and lateral articulating movements to compensate for such movements between the locomotive and tender. In order to permit ready and convenient assemblage and disassemblage of the parts 15, 16a and 16, the member 15 is formed in two portions or sections 15a and 15b, one of which is cast integral with the conduit 12 and the other formed as a separate removable part, said parts being flanged, as at 15c for passage of connecting bolts 15d, whereby the parts are adapted to be assembled and disassembled in an obvious manner. The bisecting line between these sections is preferably so placed, as clearly shown in Fig. 3, as to permit ready application and removal of the removable part 15b without interference from parts of the tender or other parts of the stoker.

The intermediate conduit 12 is provided at its forward end with a spherical coupling portion 17 which fits within a spherical socket 18 at the lower end of the elevator conduit 10, so that an articulating joint is provided at this point in the stoker line, the portions 15-16 and 17-18 thus providing joints between the stoker conduits 8, 12 and 10 to adapt the same to have free relative longitudinal and universal lateral movements to compensate for all relative movements between the locomotive and tender in service. It will be observed that the transfer unit A³ is so arranged that the greater portion thereof is at one side of its axis of articulation. This axis is a line joining the centers of the two ball joints.

In addition to the coupling and supporting connections for the elevator unit A² above described, the transfer unit A³ may be partially supported from a portion 23a of the tender frame by a sliding connection, as at 23, to relieve the joint 15-16 of a part of its weight while allowing back and forth compensating movement of said conduit as previously described. Wear plates 22a, bolted or riveted to the head of the conduit 10, may be provided to protect the side walls of the firing opening from undue wear and abrasion. The construction of the connections between the members 15-16 and 17-18 may further be such as to adapt the members of either connection or both to readily separate when the locomotive and tender are uncoupled and moved apart to facilitate the disconnection of the transfer unit from its cooperating units on the locomotive and tender.

From the foregoing it will be apparent that a universal joint has been provided between the sections 16 and 15 in which the telescopic action takes place outside the passage for fuel. It will be further apparent that the ring 16a fits over the spherical surface of the coupling 16 in such a manner that as the section 15 slides over the outer surface of the ring 16a, the latter does not move fore or aft; consequently, the center of articulation of the universal joint between the conduits 8 and 12 will always remain constant.

This application is a division of my application

Serial No. 733,142, filed June 29, 1934, for improvements in Locomotive stokers. The aforesaid application issued March 16, 1937, as United States Letters Patent No. 2,074,301.

While the structure disclosed for purpose of illustration is preferred, it will be understood that changes in the form, construction and arrangement of parts may be made without departing from the spirit of the invention, the scope of which is set forth in the appended claims.

I claim:

1. A flexible coupling comprising a rigidly mounted end section, a movable end section, said rigidly mounted end section being provided with an outer spherical surface, a ring carried by said first named end section and having an inner spherical surface fitting over the outer spherical surface thereof, a sleeve formed with said movable end section and being slidable along the outer surface of said ring, said sleeve including a portion removable therefrom and being normally disposed over said ring, and means for securing said removable portion in operative position.

2. A flexible coupling comprising a rigidly mounted end section, a movable end section, said rigidly mounted end section being provided with an outer spherical surface, a ring carried by said first named end section and having an inner spherical surface fitting over the outer spherical surface thereof, the outer surface of said ring being circular in cross section, a cylindrical sleeve formed with said movable end section and being slidable along the outer surface of said ring, said sleeve including a semi-cylindrical portion removable therefrom and being normally disposed over said ring, and means for securing said removable portion in operative position.

3. A flexible coupling comprising in rigidly mounted end section, a movable end section, said rigidly mounted end section being provided with an outer spherical surface, a ring carried by said first named end section and having an inner spherical surface fitting over the outer spherical surface thereof, a sleeve formed with said movable end section and being slidable along the outer surface of said ring, said sleeve including a portion formed integrally with said movable end section and a removable complementary portion seated upon said first named portion, and means for securing said portions in operative relation.

4. A flexible coupling comprising a rigidly mounted end section, a movable end section, said rigidly mounted end section being provided with an outer spherical surface, a ring carried by said first named end section and having an inner spherical surface fitting over the outer spherical surface thereof, the outer surface of said ring being circular in cross section, a cylindrical sleeve formed with said movable end section and being slidable along the outer surface of said ring, said sleeve including a semi-cylindrical portion formed integrally with said movable end section and a removable semi-cylindrical portion seated upon said first named portion, and means for securing said portions in operative relation.

WASHINGTON T. CAPPS.
